UNITED STATES PATENT OFFICE.

FREDERICK W. GRELL, OF NEW YORK, N. Y., ASSIGNOR TO THE AMERICAN HARD RUBBER COMPANY, OF SAME PLACE.

DESIGN FOR A COMB.

SPECIFICATION forming part of Design No. 33,612, dated November 27, 1900.

Application filed August 31, 1900. Serial No. 28,714. Term of patent 14 years.

To all whom it may concern:

Be it known that I, FREDERICK W. GRELL, a citizen of the United States, residing at New York, (College Point,) county of Queens, and 5 State of New York, have invented and produced a new and original Design for Combs, of which the following is a specification.

My invention relates to a design for combs. I will describe a comb embodying my invention.

In the accompanying drawings, Figure 1 is a front view of a comb embodying my invention. Fig. 2 is an edge view thereof.

Similar letters of reference designate corresponding parts in both of the figures.

A represents a body of a comb, and a teeth which are provided along the opposite longitudinal edges of the body. The leading or essential feature of my design consists in the body of a comb having a compound curve 20 transversely of its length. In the drawings I have shown the body as having a concavo-convex curve at its middle and reverse concave-convex curves for the portions of the body on each side of the middle. 25

What I claim as my invention is—

The design for a comb substantially as described and shown.

In testimony whereof I have signed my name to this specification in the presence of 30 two subscribing witnesses.

FREDERICK W. GRELL.
